INVENTOR
Peter Esser
BY
Charles L. Wright, ATTORNEY

UNITED STATES PATENT OFFICE.

PETER ESSER, OF CLIFTON, NEW JERSEY.

CALISTHENIC TOY.

Application filed October 11, 1921. Serial No. 507,113.

To all whom it may concern:

Be it known that I, PETER ESSER, a citizen of the United States, and a resident of Clifton, in the county of Passaic and State of New Jersey, have invented certain new and useful Improvements in Calisthenic Toys, of which the following is a specification.

The main object of this invention is to produce a toy in which a manikin, representing a child or young person, is caused to simulate the movements of the diversion known as jumping rope, the figure apparently bounding or jumping up, as the bight of the rope passes below its feet, and then assume a position of rest upon an ostensibly supporting surface as the rope completes its cycle of movement about the figure.

A further object is in the provision of a toy capable of operating in a manner descriptive of a circus ring performance in addition to the foregoing.

Another object is to provide a toy adapted for indoor amusement, particularly for girls, the toy being easily and quietly operated, capable of a high degree of ornamentation and produced at a moderate cost.

These and other like objects are attained by the novel construction, combination and arrangement of parts hereinafter described and shown in the accompanying drawings, forming a material part of this disclosure, and in which:—

Figure 1 is a perspective view showing an embodiment of the invention in its more complete form.

Figure 2 is an enlarged fragmentary sectional vertical view of the driving device used therein.

Figure 3 is a horizontal sectional view taken on line 3—3 of Figure 2.

Figure 4 is a perspective view showing a modification of the toy, simplified in its construction.

Figure 5 is an enlarged partial vertical sectional view of the same showing the driving means.

Figure 6 is a fragmentary front view showing a modified driving means.

Referring to the figures in detail, in Figures 1 to 3 of the drawings, the numeral 15 designates a flat rectangular platform mounted on a revolute axle shaft 16 fixed near its ends in wheels 17 and having a pivoted castor 18 carried in a front projection 19 in which is hinged a tongue 20.

Fixed centrally on the platform, over the axle shaft 16, is an ornamentally turned pedestal or distance piece 21 and secured on its upper end is an urn or flower pot 22, through the center of which passes a flag staff 23.

In register below the staff is a vertical shaft 24 fixed in the raised bottom of the urn and extending axially down through the pedestal and platform, its lower end having secured to it a bevel gear 25 meshing with a bevel pinion 26 fixed on the axle shaft 16, as best shown in Fig. 2, and from this it will be seen that when the truck or wheeled platform 15 is caused to travel over a flat surface that the urn will be rotated.

Revolutely mounted transversely in the walls of the urn, below its raised bottom, are spindles 27 and 28 having at their outer extending ends offset cranks 29 and 30, and near their inner end are fixed pinions 31 and 32 engaging a crown gear 33 fixed on top of the pedestal 21; thus as rotary motion is conveyed to the urn the spindles will be revolved.

A manikin or figure 34 dressed to represent a child, having its arms hanging pendant at its sides is loosely journalled on the pin of the crank 29, one of the hands 35 of the manikin appearing to grasp the crank while the other hand is engaged with one of the straight parallel sides or nodes of a stiff arched loop 36, the other side of which is pivoted to the manikin opposite the crank 29.

The feet 37 of the manikin are weighted in order to maintain the figure essentially perpendicular as it is caused to gyrate on its supporting crank about the axis of the spindle 27 while the loop 36, representing a rope, is moved in a true circular path, under the feet when the figure is raised, and over the head when it is lowered, presenting the illusion of a child jumping a rope and at the same time travelling in a circular path about the flag staff and flower carrying urn on a level horizontal plane.

The other crank 30 engages in a similar manner with the body of a figure representing a horse 38 having weighted feet 39 and provided with a saddle 40, the feet of the child and horse, when the figures are in their lowermost positions nearly or quite making contact with the platform 15.

As the horse is supported above its center of gravity its equilibrium is readily main-

tained and should it lose its balance, by the galloping movement imparted to it by the crank, it is recovered by contact of its feet with the platform.

5 Fixed on the spindle 28 is a sprocket 41 driving a chain 42 trained over another sprocket 43 fixed to a spindle 44 journaled in a support 45 extending up from the urn.

10 Formed with the outer end of the spindle 44 is a crank 46 and mounted on the crank is another figural representation of a child 47, provided with arms, hands and weighted feet, as before described, and arranged to move relative to the travel of 15 the rope loop 48, actuated by the spindle.

It is to be noted that the manikin 47 must move in synchronism to the horse 38, so that its feet may make appropriate contact with the flat saddle 40 at intervals and in 20 order to accomplish this the chain 42 is used in preference to a belt or band which might slip and cause confusion.

25 From the foregoing it will be seen that the several figures are caused to move collectively in a manner adapted to afford amusement for children and particularly as an indoor entertainment on the order of a circus performance.

30 In the modification shown in Figures 4 and 5 a wheeled truck 50 has upon its platform a simple scene representing a garden, including a fence 51 and shrubbery 52, the latter enclosing a vertical chamber 53, in the upper part of which is mounted a spindle 54 having a pulley 55 driven by a belt or cord 56 extending through the platform to a driving pulley 57 fixed on the axle shaft 58.

35 This axle shaft is mounted in the rear 40 wheels 59 and may be driven by a motor 60 of spring actuated type as shown.

45 A simpler form is indicated in Figure 6 in which a bracket 61 fixed on the platform 50, carries a spindle 62 on which a driving 50 pulley 63 is secured for actuating the belt 56, and the extending end of the spindle 54 is formed into a manually operable crank 64.

55 Fixed to the extending end of the spindle 54 is a transverse bar 65 having at one end a crank pin 66 and at the other, one of the nodes of the loop 67 which is thus caused to pass circuitously around the manikin 68 pivoted on the crank 66, the crank being supported in this case, in the fence 51, as at 69.

60 From the foregoing it will be seen that a simple device for this purpose has been disclosed in the preferred form of its embodiment, but it is not desired to restrict the details to the exact construction shown, it being obvious that changes, not involving the exercise of invention, may be made without conflicting with the scope of the 65 claims hereto appended.

Having thus described my invention, what I claim as new and desire to secure by Letters Patent, is:—

1. A toy comprising a wheeled dirigible platform, a single hollow standard thereon, a spindle revoluble transversely in said standard at the upper end thereof, cranks on the ends of said spindle, a manikin journaled above its center of gravity on one of said cranks whereby it is caused to move reciprocatively in a substantially vertical plane, a U shaped loop fixedly carried by said spindle diametrically opposite the crank, the bight of said loop passing under said manikin when the latter is raised and over the manikin when in its lowermost position, a figural element actuated by the other crank, said element having weighted feet to extend nearly to said platform and maintain the element erect by gravity, a positive gear drive wholly within said standard for actuating said spindle, said means being actuated by the wheels of said platform upon movement thereof, and a motor for propelling said platform. 70 75 80 85 90 95

2. A toy comprising a single standard, a spindle mounted transversely therein, said spindle having an extending crank, a manikin journaled at its waist line on said crank, a wheeled platform carrying said standard and upon which the lower extremity of said manikin makes contact when in its lowermost position whereby it is maintained substantially horizontal, a loop carried by said spindle adapted to move circumambiently of said manikin, an upright arm fixed on said turntable, a spindle revoluble in the upper portion of said arm, said spindle having a crank, a second manikin supported and actuated by said crank, means to communicate rotary motion between said spindles, a figural object on the ends of the first named spindle, means to actuate said object conjunctively with said manikin; a motor for actuating the axle of 100 105 110 115 120 125 130 said platform, and operative connections between the axle and said first named spindle.

3. A toy comprising a wheeled dirigible platform having an axle fixed in the rear 115 wheels, a standard on said platform, a turntable on the standard, a vertical shaft in said standard geared to said axle for rotating said turntable, a crown gear fixed on said standard, opposed transverse spindles 120 rotatable in said turntable, pinions on said spindles meshing with said crown gear, cranks on the outer ends of the spindles, a figural object journaled on one of said cranks whereby it is raised and lowered, a manikin on the other crank, and means for passing a loop circuitously around said manikin as it is raised and lowered by its crank. 125

4. A toy comprising a wheeled dirigible 130

platform, a standard thereon, a turntable rotatable on the standard, means actuated by the wheels of said platform for rotating said turntable, a crown gear fixed on said standard, spindles rotatable transversely in said turntable, pinions on said spindles meshing with said crown gear, cranks on the outer ends of the spindles, a figural object journaled on one of said cranks whereby it is raised and lowered, a manikin on the other crank, a second manikin supported over the figural object, means for raising and lowering said second manikin relative to the object, loops rotatable about said manikins, the axis of rotation of said loops passing transversely therethrough, and means for maintaining said manikins substantially erect irrespective of their circuitous and reciprocal movements.

5. A toy comprising a wheeled platform having an axle fixed in the rear wheels, a standard on said platform, a turntable on the standard, a vertical shaft in said stand-

ard geared to said axle for rotating said turntable, a crown gear fixed on said standard, opposed transverse spindles rotatable in said turntable, pinions on said spindles meshing with said crown gear, cranks on the outer ends of the spindles, a figural object journaled on one of said cranks whereby it is raised and lowered, a manikin on the other crank, a post fixed to extend above said turntable, a cranked spindle journaled in said post parallel to the spindle on which said figural object is mounted, positive driving connections between said spindles, a second manikin and loop engaged with the cranked portion of the last named spindle, and loops driven by the crank supporting the respective manikin to pass circumambiently therearound.

10 15 20 25 30 35 40

In testimony whereof I have signed my name to this application.

PETER ESSER.
